UNITED STATES PATENT OFFICE.

ERTHOLD C. JANKE, OF MILWAUKEE, WISCONSIN, ASSIGNOR TO JAYEM MANUFACTURING COMPANY, OF MILWAUKEE, WISCONSIN, A CORPORATION OF WISCONSIN.

FASTENING MEANS FOR BOOTS.

Application filed January 23, 1926. Serial No. 83,285.

The invention relates to boots and more particularly to improvements in fastening and re-enforcing means for such boots.

The provision of a rapidly-operable fastener on a lacing boot, as disclosed in my co-pending application for boots, Serial No. 46,315, filed July 27, 1925, and also in my co-pending application for shoes, Serial No. 704,191, filed April 4, 1924, has been found 10 very convenient as the operation of placing the boot on the foot and removing it therefrom is greatly simplified, in addition to affording proper fitting of the boot to the foot. In some instances, however, the fabric of the 15 fasteners commonly used was found to deteriorate rapidly, particularly when exposed to organic acids or other harmful substances, thereupon necessitating the replacement of the fasteners.

It is an object of the present invention to provide a boot which may be rapidly placed on the foot and removed therefrom by means of separable fasteners such as clasps, and in which suitable means are provided to insure 25 snug fitting and neat appearance without interfering with the flexibility of the boot.

Another object of the invention is to provide a boot of this character in which localized pressure of the fasteners on the foot is 30 avoided.

A further object of the invention is to provide a boot of this character which is capable of withstanding hard service and which can be inexpensively manufactured.

The invention further consists in the several features hereinafter set forth and more particularly defined in the annexed claims.

In the accompanying drawings Fig. 1 is a perspective view of a high boot embodying 40 the invention;

Fig. 2 is a sectional view thereof taken on the line 2—2 of Fig. 1;

Fig. 3 is a fragmentary detail view showing the manner of re-enforcing one quarter 45 of the upper; and

Fig. 4 is a fragmentary detail view showing the manner of re-enforcing a fastener strip for the boot.

In these drawings, 10 indicates a boot in 50 which the upper 11 is parted at its forward portion, the outer quarter of the upper being provided with a row of eyelets 12 for a centrally disposed lacing 13. To correspond with the eyelets 12, a complementary row 55 of eyelets 14 is placed in a fastener strip 15

of leather or other suitable material. The lower end of the fastener strip 15 is provided with a laterally projecting part 16 registering with the edge of the adjacent quarter, both being sewn to the vamp 17 by the same 60 line of stitching 18. For the blucher type of boot shown in the drawings, the forward lower edge of the upper terminates short of its usual position and the adjacent overlapping edges of the upper and fastener strip 65 are skived at 19 to present a joint of neat appearance. The fastener strip is preferably located at the inner quarter of the upper, as noted above, and substantially in line with the high portion of the instep to afford 70 a large opening for insertion of the foot into the boot.

The fastener strip 15 overlaps the upper throughout its length, as shown in Figs. 1 and 2, and is provided with spaced eyelets 20 75 adapted to receive therethrough the hooked levers 21 of lever clasps 22, which may be of the type commonly used in arctics. The bases 23 of the clasps are secured to the upper by rivets 24 or other suitable fastening means. 80

The rivets may also extend through a gusset 25, secured to the inside quarter of the upper by suitable stitching and folded at the opposite side with its edge secured to the other quarter of the upper along the row of 85 eyelets 12, thus furnishing a closed gusset in which there is but one fold disposed at the outside quarter of the boot.

As distinguished from conditions met with in overshoes, which have a comparatively 90 loose fit, the spaced clasps 22 are subject to considerable strain incident to the snug fitting of the boot on the foot, which ordinarily would cause unsightly gaping and uncomfortable localized pressure on the foot. In 95 addition, it would prevent the effective use of the lacing since the portion of the fastener strip between the clasp eyelets would yield and buckle under the tension of the lacing; also, the portion of the upper to which the 100 clasps are secured would have a similar tendency to buckle and yield.

In order to avoid such tendencies and to obviate the use of an inconveniently large number of clasps, which would defeat the 105 object of the invention, re-enforcing means are provided for the fastener strip and the upper. The fastener strip 15 carries an inner facing 26 suitably stitched thereto and narrow pockets are formed between them to 110

receive longitudinally extending flat spring metal strips 27 and 28. These spring strips are preferably disposed along the edge of the fastener strip which engages the upper, so that the clasp eyelets 20 lie between the spring strips and the eyelets 14, thereby better resisting yielding of the strip and concealing the clasp bases 23. The strips 27 and 28 are conveniently formed in straight pieces and a gap is left between them in the region of the ankle bone where the greatest amount of flexibility is needed. This gap also serves to relieve any pressure on the projecting ankle bone, and because of the elevation at this region, the fastener strip will remain in close proximity to the upper without tendency towards gaping.

The upper 12 is also provided with similar spring metal strips 29 and 30 disposed in similar relation, and these strips are held in narrow pockets formed between the upper and the gusset 25. In some cases it has been found that the lower short spring metal strip 30 may be omitted. The spring metal strips 29 and 30 are preferably disposed below the pivotal portions of the lever clasps, in order to prevent uncomfortable localized pressure of the clasps on the foot and leg.

The spring metal strips 27 to 30 may be laminated for greater flexibility and are preferably provided with rounded tips 31 to avoid cutting through the stitched pockets in which the strips are retained.

The boot is first placed on the foot with the lacing open and the clasps closed onto the fastening strip 15. The gusset 25 is then smoothed to assume the position shown in Figs. 1 and 2 presenting only a single fold at one side, following which the lacing is adjusted to obtain the proper fit and then tied. Although the clasps are placed at a considerable distance apart, there is no tendency during the lacing operation for the fastener strip to buckle or gape, since the spring metal strips 27 and 28 are incapable of any substantial yielding in their plane. For subsequent removal of the boot the levers 21 of the clasps are swung open, whereupon the laced portion of the upper is swung outwardly from the foot to permit easy removal of the foot. When opening the boot, it is not necessary to separately manipulate each clasp lever as the several clasps may be opened by pulling the fastener strip 15 outwardly at its outer and upper edge and thereby swinging the levers outwardly one after the other as the strip is forced open along the foot. The boot may thus be opened in a very rapid and expeditious manner. This method of opening the boot makes it possible for the clasp levers to engage the fastener strip close to their free ends so that grass or other growth will not become caught under the levers.

Thereafter the boot is placed on the foot with the clasps open, the gusset being readily smoothed and adjusted by passing one hand through the opening left by the fasteners and moving the hand along to properly position the fold. It is then only necessary to guide the levers of the clasps through the eyelets 20 and to swing the levers shut with the "pulling over" effect which accompanies the operation of these clasps, thereby insuring a snug fitting boot. The manipulation of the clasps requires very little time as compared with a lacing operation and the lacing remains in its initially adjusted position to insure a properly fitting boot.

The boot of the present invention is capable of withstanding the hard service encountered when worn about the farm and can be manufactured at a cost but slightly more than the conventional boot. The spring metal re-enforcing strips are quite flexible at right-angles to their plane and do not in the least interfere with comfortable walking. The flexibility of these strips also permits the boot to be rolled up in the usual manner for purposes of shipment.

The term boot, as herein employed, includes such obviously similar articles of apparel as gaiters, spats and leggings.

What I claim as new and desire to secure by Letters Patent is:

1. In a boot, the combination with an upper having a lacing for adjusting the boot on the foot, of spaced separable fasteners secured to said upper adjacent the lacing and adapted for effecting rapid opening and closing of said upper after initial adjustment of said lacing, and re-enforcing means disposed along the upper adjacent the fasteners and being relatively unyielding in the plane of the upper but comparatively flexible normal to the plane of the upper.

2. In a boot, the combination with an upper having a lacing for adjusting the boot on the foot, of spaced separable fasteners secured to said upper adjacent the lacing and adapted for effecting rapid opening and closing of said upper after initial adjustment of said lacing, and a flat flexible metal re-enforcing strip disposed along the upper adjacent said fasteners.

3. In a boot, the combination with an upper having a lacing for adjusting the boot on the foot, of spaced separable fasteners secured to said upper adjacent the lacing and adapted for effecting rapid opening and closing of said upper after initial adjustment of said lacing, and a pair of flat flexible metal strips disposed along the upper adjacent said fasteners and having their adjacent ends in the region of the ankle bone.

4. In a boot, the combination of an upper having a lacing for adjusting the boot to the foot and including a fastener strip re-

- ceiving said lacing at one edge, a flat flexible metal re-enforcing member carried by said strip at its opposite edge and separable fasteners carried by the upper and engaging 5 said strip along its intermediate portion.
5. In a lacing boot, the combination of an upper having a fastener strip overlapping the adjacent quarter of said upper, separable fasteners joining said fastener 10 strip and quarter, and flat flexible metal re-enforcing members carried by said strip and quarter adjacent said fasteners, one of said re-enforcing members being disposed below said fasteners to avoid localized pressure of 15 said fasteners on the foot.
6. In a boot, the combination of an upper including a fastener strip, separable fasteners joining said upper and fastener strip, and a pair of flat flexible metal re-enforcing 20 members carried by said fastener strip and having their adjacent ends spaced in the region of the ankle bone.
7. In a boot, the combination of an upper having a fastener strip overlapping the 25 adjacent quarter of said upper and receiving a lacing at one edge, a flat spring metal
- re-enforcing member carried by said strip at its opposite edge, spaced eyelets disposed along said strip between the lacing and said re-enforcing member, and clasps secured to 30 said upper and including pivoted levers received through said eyelets.
8. In a boot, the combination of an upper having a front central lacing for adjusting the boot to the foot and including a fastener 35 strip receiving said lacing at one edge and projecting from the forward and lower edges of a subjacent quarter to which it is secured at its lower end, separable fasteners joining said fastener strip and the subjacent 40 quarter, and flexible re-enforcing means carried by said strip relatively unyielding in the plane of said strip.
9. In a boot, the combination of an upper having a lacing for adjusting the boot to the 45 foot and including a fastener strip receiving said lacing, spaced separable fasteners joining said upper and fastener strip, and flexible re-enforcing means for said strip relatively unyielding in the plane of said strip. 50

In testimony whereof I affix my signature.
ERTHOLD C. JANKE.
